UNITED STATES PATENT OFFICE.

FRANK H. CRUMP, OF LOS ANGELES, CALIFORNIA.

BOOKBINDING.

1,093,825.

Specification of Letters Patent. Patented Apr. 21, 1914.

Application filed April 19, 1912. Serial No. 691,898.

To all whom it may concern:

Be it known that I, FRANK H. CRUMP, citizen of the United States, residing at Los Angeles, in the county of Los Angeles and State of California, have invented certain new and useful Improvements in Bookbinding, of which the following is a specification.

This invention relates to binders and more particularly to binders of that type in which the leaves are held upon posts secured through cover plates. Such binders as usually constructed have their posts secured to the bottom cover-plate, and the top cover-plate is adjustably mounted upon the posts, means being provided for clamping the said top cover plate at adjustment. Such construction however, presents the disadvantage that the projecting ends of the posts are liable to scratch the surface of the desk upon which the binder is placed, and prevent one binder being placed upon another.

The present invention aims, therefore, to provide a binder of this type in which it will be unnecessary to provide any clamping means upon the posts and in which the posts, while firmly holding the cover plates in place, will not project beyond the cover plates and consequently, will not scratch a desk or table on which the binder is disposed.

For a full understanding of the invention reference is to be had to the following description and accompanying drawing, in which:—

Figure 1 is a perspective view of the binder embodying the present invention. Fig. 2 is a vertical longitudinal section view therethrough taken in a plane with one of the posts. Fig. 3 is a vertical sectional view through a slightly modified form of the binder. Fig. 4 is a perspective view of this form of binder. Fig. 5 is a perspective view of one of the posts of the binder, the post being partly in section.

Corresponding and like parts are referred to in the following description and indicated in all the views of the accompanying drawing by the same reference characters.

In the drawing, and particularly in Figs. 1 and 2 thereof the bottom cover plate is indicated by the numeral 1 and the top cover plate by the numeral 2, and the leaves which are confined by these plates by the numeral 3. The top and bottom plates are covered with cloth, as usual, and are con-

nected by the cloth covering, as at 4, with the strips to which the leaf holding posts of the binder are secured. That strip to which the bottom plate 1 is connected is indicated by the numeral 5, and is preferably of metal, and the leaf holding posts above mentioned, and indicated at 6, have their lower ends riveted as at 7 in openings 8 formed in the said strip 5. The posts 6 are tubular as shown in the drawings and at their upper ends they are engaged through openings 9 formed in a strip 10 corresponding to the strip 5, and through openings 11 in a strip 12 which is preferably of pasteboard or like material, and is secured against the upper side of the strip 10. It will be observed from an inspection of Fig. 2 of the drawing that the openings 11 are of greater diameter than the openings 9, and that the said openings 11 register with openings 13 in that portion of the cloth cover for the cover plate 2 and its related strip 10. After the desired number of sheets 3 has been assembled with the posts 6, the upper ends of the posts are inserted through the openings 9, 11 and 13 and pressure is exerted against the strips 5 and 10 so as to firmly compress the confined ends of the said leaves 3. The projecting end of each post 6 is then severed by the use of a pair of pliers or any similar implement, as clearly shown in the drawing and indicated by the numeral 14. In severing the projecting ends of the posts, the said ends are flattened, as will be readily understood, and thus, as a result of the severing operation, not only are the projected ends of the posts removed, but the posts at their upper ends are at the same time headed.

By referring to Fig. 2 of the drawing it will be observed that due to the fact that the openings 11 are of greater diameter than the openings 9, the heads 14 will not project beyond the surface of that portion of the cloth cover which extends over the top of the strip 12. Consequently the binder may be placed on a desk or table, either side uppermost, without likelihood of scratching the finish of the desk or table.

When it is desirable to produce a binder even less expensive to manufacture than the one shown in Figs. 1 and 2 of the drawing, the cover plates 1 and 2 are dispensed with and strips 15 of cardboard, or like material are disposed one against the under side of the lowermost sheet and the other against

the upper side of the uppermost sheet of the stack to be bound. These strips 15 are formed with openings 16 which register with the openings in the sheets or leaves. A 5 washer 17 is disposed against the under side of the lowermost strip 15 and has its opening registering with the opening 16 in the said strip, and in a like manner a washer 18 is disposed against the upper side of the 10 strip 15 at each opening 16 therein and these washers have their openings registering with the said openings 16. The posts of this form of binder are indicated by the numeral 19 and each is provided at its lower end with a 15 head 20 bearing against the under side of the washer 17. The upper end of each post is headed as at 21 in the same manner as the upper ends of the posts 6, previously described. It is preferable that the washers 17 20 and 18 be of plano-concavo form so as to house the heads 20 and 21 of the said posts and thereby prevent these heads scratching the finish of the desk or table upon which the binder is disposed.

25 Having thus described the invention what is claimed as new is:—

1. In a binder, spaced leaf-confining members, a tubular post carried by one member, the other member being formed with an 20 opening receiving one end of the tubular post and being formed with a recess located at the opening, the said end of the post be-

ing laterally compressed and thereby expanded laterally to form a head of a width greater than the diameter of the said opening and received in the recess. 35

2. In a binder, leaf confining members, a tubular post secured at one end to one of said members, the post projecting at its other end through the other member, the last-mentioned end of the post being compressed laterally and thereby expanded to form a transverse head flared in the direction of its extremity. 40

3. In a binder, spaced leaf-confining members, one of said members including a strip, a tubular post fitted at one end through the strip and provided at its said end with a head bearing against one side of the strip, the other leaf-confining member including a strip formed with an opening through which the other end of the post projects, the said post at its last mentioned end being compressed and thereby expanded laterally whereby to form a diametrically extending 50 head of a width greater than the diameter of the post. 55

In testimony whereof I affix my signature in presence of two witnesses.

FRANK H. CRUMP. [L. S.]
